L. KIRK.
AIR BRAKE.

No. 23,923.

Patented May 10, 1859.

UNITED STATES PATENT OFFICE.

LEWIS KIRK, OF READING, PENNSYLVANIA.

IMPROVEMENT IN RAILROAD-CAR BRAKES.

Specification forming part of Letters Patent No. 23,923, dated May 10, 1859.

To all whom it may concern:

Be it known that I, LEWIS KIRK, of the city of Reading, in the county of Berks and State of Pennsylvania, have invented a new and Improved Car-Brake; and I do hereby declare that the following is a full, clear, and exact description of the same, reference being had to the accompanying drawings, in which—

Figure 1 represents a longitudinal vertical section of a railroad-car with my brake arrangement, the line $x x$, Fig. 2, indicating the plane of section. Fig. 2 is a plan or top view of the same, in which the platform of the car has been removed. Fig. 3 is a horizontal section of the pump which I use for operating the brakes, the line $y y$, Fig. 4, indicating the plane of section; and Fig. 4 is a transverse vertical section of this pump, taken in the plane indicated by the line $z z$, Fig. 3.

Similar letters of reference in the several figures indicate corresponding parts of my invention.

The object of this invention is to employ hydrostatic pressure for the purpose of operating the brakes of a railroad-car; and the invention consists in a peculiar construction of the pumps employed and in a certain arrangement of rods, levers, and arms, in connection with the pumps, both of which will be herein-after described, so that the pumps may be operated either by a hand-wheel or by means of the pressure with which the cars act on the couplings.

To enable others skilled in the art to fully understand and construct my invention, I will proceed to describe the same.

A is the platform of a railroad-car, of the usual construction, and a pump, B, is attached to the under side of this platform and about in the center of the same. This pump consists of one main cylinder, C, with two pistons and two pump-cylinders, D D', the bore of which is considerably smaller than the bore of the main cylinder C. The interior arrangement of this pump is clearly represented in Figs. 3 and 4. The three cylinders C and D D' are connected by passages $a a'$ and $b b'$, which extend from the valve-chambers $c c^* c' c'^*$ to cavities d , from which passages e run through to the interior of the main cylinder C and to that part, d' , of the same which is left free between its two pistons, and other passages, a^* and b^* , extend from the upper part of the valve-cham-

bers $c c^* c' c'^*$ to those parts of the main cylinder which are on the outside of its pistons. The valve-chambers $c c^*$, as well as those $c' c'^*$, communicate by means of cocks E and E', as represented in Fig. 4. The lower part of the valve-chamber c extends into a cavity, e , which communicates with the passage f in the cock E, and the cavity e at the same time communicates with the cavity g , from which a passage, h , leads into the interior of the main cylinder C. The valve-chamber c^* communicates with a cavity, e^* , which communicates with another cavity, g^* , from which a passage, h^* , leads on one side into the interior of the main cylinder, and on the other side into the passage f in the cock E. If the cocks E and E' are turned to such a position that the passage f is not in communication with the valve-chambers, the water forced by the pistons of the pump-cylinders is forced through the passages $a a' b b'$ to the outer ends of the main cylinder, and its pistons are forced together. If, however, the cocks E E' are in a position as represented in Fig. 4, the water forced by one of the pump-cylinders runs right through to the other one and circulates through the pump without affecting the pistons of the main cylinders. In the first case, the water taken from the part d' between the pistons of the main cylinder is used to force the two pistons together. In the latter case the water drawn in by one of the pump-cylinders from the space d' returns to the same through the passage f without moving the pistons of the main cylinder. By opening the cocks E E' the pressure which may act on the outside of these pistons is taken off in an instant.

The piston-rods $c^2 c'$ of the two pistons C² and C³ of the main cylinder connect with the levers F F', and the lever F, which is attached to the beam H by means of an arm, f^* , connecting with the brakes F^{*} of the truck I by means of rods f' and f^2 . In the same manner the lever F', which is attached to the beam H' by means of an arm, f'^* , connects with the brakes F^{*} of the truck I'. Spiral springs i are placed on each of the rods c^2 and c' , which force the pistons back as soon as the pressure is taken off, which is done by opening the cocks E and E'. The piston-rods d^2 and d^3 of the pump-cylinders extend out on different sides, and the piston-rod d^2 is connected to a crank, J, which is attached to a vertical axle, K, which

may be rotated by means of a hand-wheel, J' , and close by this axle J is a rod, K , which is operated on by the foot, and which connects with the cock E' by means of a bell-crank, e^2 , and a rod, e^2k , so that the cock E' is closed by depressing the rod K with the foot. The piston-rod d^3 on the other side has its bearing in the cross-beam H' , and it is provided with a spring-catch, k , which works in a slot made into a square part, d^3k , of the piston-rod, and which is attached to the same by means of a pivot, k' . A spring, k^2 , serves to raise the catch k , and a bell-crank, l , which is hinged to the cross-beam H' , extends with one of its arms, l' , through the slot in the square part d^3k of the piston-rod d^3 . The other arm, l'' , of the bell-crank l is attached to an eccentric-ring, m , which fits over an eccentric-disk, m' , on the axle n of one of the wheels, W , in the truck I' . If the catch k is raised, the arm l' of the bell-crank l , which has a vibrating motion by the eccentric, moves without touching the same; but if the catch k is depressed into the slot in which it is fastened the arm l' strikes against the same and the piston-rod d^3 receives a reciprocating motion, whereby the water is forced into the main cylinder C if the cock E is in the proper position.

The catch k is operated upon by means of a cam, O , which is attached to a rod, p , which extends through the whole length of the car, and another cam, q , is fastened on this rod, which works in a socket, r , which is attached to a rod, s . This rod has one of its bearings in the platform of the car and the other one in a hanger, t , and it extends beyond the platform, so that it can be depressed by the foot. The lower end of the rod s is connected to a crank, u , by which the cock E is operated. A hand-lever, L , is attached to one end of the rod p , and to the other end of the same the

coupling M is attached, which is so arranged that by pressing on the same the rod p is turned sufficiently to close the cock E and to depress the catch k . In this case the pump-cylinder D will force water into the main cylinder, and the brakes will be applied until the wheel W , to the axle of which the eccentric m' is attached, ceases to revolve. In the same manner by turning the hand-lever L the catch k may be depressed, and as the cock E is closed at the same time by the action of the cam q on the rod s the pump-cylinder D begins to operate and the brakes are applied until the wheel W ceases to revolve.

Having thus described my invention, what I claim as new, and desire to secure by Letters Patent, is—

1. The arrangement of the hand wheel J and the rod K , in combination with the pump B , so that by depressing the rod K the pump is placed in working order, and that the same can be operated by means of the hand-wheel J' , substantially as described.

2. The arrangement of the spring-catch k , which is attached to the piston-rod d^3 of one of the pump-cylinders, in combination with the bell-crank l , or its equivalent, which is operated by means of an eccentric, m' , substantially as and for the purpose set forth.

3. Arranging the coupling M on a rod, p , in such relation to the spring-catch k and to the cock E that by exercising a pressure on the coupling the rod p is turned sufficiently to open the cock E and to depress the spring-catch k , substantially as and for the purpose described.

LEWIS KIRK.
